UNITED STATES PATENT OFFICE.

ABRAM S. MANN, OF ROCHESTER, NEW YORK.

LACE-FASTENER.

SPECIFICATION forming part of Letters Patent No. 379,968, dated March 27, 1888.

Application filed September 7, 1885. Serial No. 176,323. (No model.)

To all whom it may concern:

Be it known that I, ABRAM S. MANN, of the city of Rochester, in the county of Monroe and State of New York, have invented a certain 5 new and useful Improvement in Lacings; and I do hereby declare that the following is a full, clear, and exact description of the same, reference being had to the drawings accompanying this application.

10. My improvement relates to lacings for gloves, corsets, shoes, &c.; and it consists of a device for securing or fastening the ends of the lacing-cords when drawn up taut.

The invention consists in the combination, 15 with the article to be laced and with the lacing cord or cords, of a button with beveled sides secured on the outside of the fabric and a stiff disk on the inner side, the two being placed in juxtaposition and attached close together, thereby forming a wedge-shaped space 20 between them, into which the cord is drawn, and is held by the rigidity of the two bodies, as hereinafter more fully set forth.

In the drawings, Figure 1 is a face view of 25 a glove with the lacing applied thereto. Fig. 2 is a diagram showing a plan view of the fastening device enlarged. Fig. 3 is a vertical section of Fig. 2. Fig. 4 is a view similar to Fig. 3, but showing a modification.

30. The drawings show a glove to which the lacing is applied. The lacing-cord *a* is passed alternately around the studs *b*, as usual, and is drawn up and fastened at the top. It may be applied to corsets, shoes, or analogous articles in similar way, and, if desired, two or 35 more lacing-cords may be used.

My improvement is as follows:

c is a button or similar device fastened to the outside of the fabric at the point where the 40 cord is to be drawn up. The button or head is formed upon one side with a conical part, *d*, and a plain or flat central part, *e*, Fig. 3.

f is a stiff disk on the under or inner side of the fabric, also securely fastened in place in juxtaposition with the exterior button. The 45 disk is of such diameter that its edges project beyond the perimeter of the flat part *e*, the button and disk when thus arranged including between them a conical annular space, into which the lacing-cord may be wound by giving it two or three turns around the button on the outside, no other fastening being required, and the coils of the cord holding by their own binding and contact. It is necessary to secure the button and disk together so firmly 50 that there shall be no yielding between them, and a convenient way is to use a single rivet or holder, as shown in Fig. 3, or a double one, as shown in Fig. 4. Any other suitable means 55 may be used.

The above forms a more secure and convenient fastening than the clasps and hooks now generally in use, and also the studs heretofore used for a similar purpose.

I disclaim a fastening consisting of two 65 spring-plates connected by a rivet.

What I claim as new is—

The herein-described fastening for the ends of lacing-cords, comprising a button having a plain upper surface, an inclined or frusto-conical under portion terminating in a reduced flat bearing-surface, in combination with suitable fastening devices, and a rigid washer or disk secured to the under surface of the material, said disk or washer being larger than 70 the under bearing-surface of the button, substantially as described.

In witness whereof I have hereunto signed my name in the presence of two subscribing witnesses.

ABRAM S. MANN.

Witnesses:

R. F. OSGOOD,
JACOB SPAHN.
